UNITED STATES PATENT OFFICE.

BERNARD S. LEE, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WAX-THREAD SEWING-MACHINE.

1,313,704.

Specification of Letters Patent.

Patented Aug. 19, 1919.

Application filed May 3, 1915. Serial No. 25,471.

To all whom it may concern:

Be it known that I, BERNARD S. LEE, a citizen of the United States, residing at Beverly, in the county of Essex and State of Massachusetts, have invented certain new and useful Improvements in Wax-Thread Sewing-Machines; and I do hereby declare the following to be a full, clear, and exact description of the invention, such as will 10 enable others skilled in the art to which it appertains to make and use the same.

This invention relates to wax thread sewing machines, and more particularly to heating devices for such machines.

15 Certain features of the invention relate particularly to wax thread sewing machines of the type comprising a straight hook needle, and devices coöperating therewith to form a chain stitch seam in which the shoe is supported during the sewing operation upon a rotatable horn, such sewing machines being generally known in the art as sewing machines of the McKay type. Other features of the invention are generally applicable to 20 wax thread sewing machines in which the thread is passed through a receptacle containing melted wax on its way from the supply to the work to impregnate the thread with wax.

25 One object of the present invention is to provide wax thread sewing machines with heating devices for maintaining the wax in the wax receptacle in a properly melted condition along the path of the thread having 30 an improved construction and mode of operation.

Another object of the invention is to provide wax thread sewing machines of the McKay type with an improved and highly 35 efficient electrical heating system for heating the horn and other parts of the machine and for heating the wax in the wax receptacle.

With these objects in view, the features 40 of the invention consist in the novel and improved constructions and combinations hereinafter described and particularly pointed out in the claims, the advantages of which will be obvious to those skilled in the 45 art.

The features of the invention will be readily understood from an inspection of the accompanying drawings illustrating a machine embodying the invention in its pre-

fferred form and the following detailed description thereof.

In the drawings, Figure 1 is a view in side elevation of a shoe sewing machine embodying the invention; Fig. 2 is a detail view partly in rear elevation and partly in section, illustrating particularly the construction of the horn and certain associated parts; Fig. 3 is a detail sectional view taken through the wax receptacle; Fig. 4 is a plan view of the wax receptacle and certain associated parts; Fig. 5 is a view in side elevation, partly in section, of the wax receptacle and certain associated parts; Fig. 6 is a detail view in horizontal section taken through the horn spindle, and Fig. 7 is a sectional view taken substantially on the line 7-7 of Fig. 6.

The machine illustrated in the drawings is a sole sewing machine of the so-called McKay type, having substantially the same general construction, arrangement and mode of operation of parts as the machine illustrated in the patent to Scott No. 1,050,568, dated January 14, 1913. This machine comprises a straight hook needle and devices coöperating therewith to form a chain stitch seam, and a rotatable horn arranged to extend inside the shoe to support the same during the sewing operation and carrying a looping device within its tip by which the thread is laid in the hook of the needle. In the construction shown, the horn proper indicated at 8, is mounted upon a base 10 which is secured to the upper end of the horn spindle 12, and is arranged to rotate upon ball 15 bearings 14 carried by the forwardly projecting arm 16 of the frame of the machine, the horn spindle extending downwardly through a suitable opening in this arm. The lower portion of the horn spindle consists of a 20 hollow shaft 18 extending within and secured to the upper portion of the spindle, the reduced lower end of which shaft is stepped into a bearing in the upper end of a bushing 20 driven into a bore in the forwardly extending arm 22 on the frame, the engagement of the shaft 18 in this bearing serving to steady the horn. A second bushing 24 is driven into the bore in the arm 22, from the lower side of the arm. Within 25 the horn spindle is mounted the whirl operating shaft 26 having a bearing at its lower end in the bushings 20 and 24 and engaging

at its upper end in a bearing in the block 28 mounted in the upper end of the horn spindle. This shaft carries at its upper end a gear 30 connected through suitable gearing 5 with the whirl located in the horn tip. The shaft 26 is driven through the beveled gears 32 from the horizontal shaft 34 which is connected by a train of gearing with the main shaft 36 in the head of the machine.

10 The wax receptacle 36^a is fixed to a base plate 38 mounted upon the horn base 10. The container 40 for the thread supply is mounted upon a shelf 42 formed by an extension of the base plate 38 of the wax receptacle, as shown in Figs. 1 and 5. To give access to the parts in the lower portion of the horn proper and at the top of the horn spindle which are obstructed by the wax receptacle when this receptacle is located in 15 operating position, as shown in Fig. 1, the wax receptacle is mounted to slide outwardly upon the horn base 10 to expose these parts. The wax receptacle is held in operating position upon the horn base 10 by means of 20 the screw 44 engaging in a slot in the horn base and screwed into the base plate 38 of the wax receptacle. The thread passes from the supply 46 located in the container 40 through a central opening in the spider 48 25 mounted on the top of the container and then passes downwardly through an opening 50 in the cover 52 of the wax receptacle into the wax receptacle.

The cover for the wax receptacle consists 30 of a plate fixed to the top of the receptacle upon which are mounted the devices for guiding the thread in its passage through the receptacle, the heating devices for maintaining the wax in the receptacle in a suitably melted condition, the stripping devices 35 for stripping the wax from the thread as it emerges from the receptacle, and the tension device for maintaining the thread under suitable tension. In the construction 40 shown, an arm 54 mounted upon the cover of the wax receptacle extends downwardly into the receptacle to a point near its base and carries at its lower end a thread truck 56 about which the thread extends in its 45 course through the receptacle, as shown particularly in Fig. 3, so that the thread is immersed in the melted wax as it passes through the receptacle. A thread guide 58 having an eye through which the thread 50 passes, is formed on the arm 54, this guide acting to prevent the thread from running off the thread truck 56. As the thread emerges from the wax receptacle, the surplus wax is stripped from the thread by 55 means of a stripping device mounted on the cover of the receptacle. This stripping device is of well known construction and consists of a shaft or bar 60 fixed by means of a set screw 62 in a suitable bore in the cover 60 of the wax receptacle, this bar having a

groove in which the thread is engaged as it passes over the bar. A flat spring plate 64 fixed to the cover of the wax receptacle is arranged to press upon the thread as it passes over the bar 60, the wax being 70 stripped from the thread by the co-operative action of the spring and bar. After passing through the stripping device, the thread is wrapped about the thread wheel of the tension device. This tension device is also of 75 well-known construction and comprises a thread wheel 66 mounted upon a shaft 68 fixed to the cover of the wax receptacle and a friction brake for retarding the rotation of the thread wheel. This brake comprises 80 a brake member 70 carried by a sleeve 72 and normally held in engagement with a brake member carried by the thread wheel by means of the spring 74 interposed between the sleeve and the abutment 76. After 85 leaving the tension device, the thread passes into the lower portion of the horn proper and then extends upwardly over the thread trucks 78 and 80 to the whirl located in the tip of the horn. 90

In the present embodiment of the invention, the machine is provided with a heating system adapted for the use of electricity as a heating medium and constructed and arranged to apply heat to the machine at two 95 principal points. This system comprises a heating unit mounted in the wax receptacle to maintain the wax in the receptacle in a suitable condition to be applied to the thread as the thread passes through the receptacle, 100 and a second heating unit mounted in the horn to keep the horn heated so as to prevent the chilling of the wax thread as it passes from the wax receptacle to the looping device in the tip of the horn. 105

The heating devices for the wax receptacle comprise an arm 82 mounted on the cover of the receptacle and extending downwardly into the receptacle substantially parallel with the arm 54. The arm 82 is formed 110 with a cylindrical chamber or pocket 84 in which is mounted an electrical heating unit 86. This heating unit consists of a series of heating coils embedded in insulating material, the terminals 88 of which are suitably connected with the main circuit terminals. The arm 54 which carries the thread truck 56, is connected with the arm 82 by means of a web 90 through which the arm 54 is heated by conduction. To increase the heat radiating area of the arm 82, this arm is formed with radially projecting blades or plates 92, as shown in Fig. 4. The heat transmitted from the arm 82 in which the heating unit is mounted, keeps the wax adjacent thereto 115 in a thoroughly melted condition, so that it flows toward the point where the thread passes through the receptacle as the wax is used up by the thread. The arm 54 is kept hot chiefly by conduction through the web 120 125 130

- 90 from the arm 82 and the wax is kept properly melted adjacent the path of the thread by the heat transmitted by this arm. The heat transmitted chiefly by conduction from 5 the arm 82 to the stripping device and the thread wheel of the tension device keeps these parts hot so that the thread does not become chilled after it leaves the wax receptacle.
- 10 The construction for heating the horn comprises a composition metal block 94 having a relatively high co-efficient of conductivity mounted in the horn, as shown in Figs. 1 and 2, and having a cylindrical chamber 15 96 to receive an electrical heating unit 98 similar to the unit 86, the terminals 100 of which are suitably connected with the main circuit terminals. The heat transmitted from the heating unit 98 through the composition metal block 94 serves to keep the 20 horn hot and the thread is thus kept in proper condition as it passes through the horn to the whirl.
- In the system of electrical circuits illustrated in the drawings, the electrical heating units 86 and 98 are arranged in parallel and a rheostat is connected in the circuit leading to these units to enable the heat generated thereby to be conveniently controlled. The terminals 88 of the electrical heating unit 86 are connected with the secondary circuit wires 106 leading to this unit by means of a flat iron plug. To the ends of the terminal wires 88 are connected the plug members 35 108 mounted in an insulating block 110 fixed to the side of the wax receptacle. The ends of plug members 108 are adapted to be inserted in sockets in the coöperating plug members 112, each connected with one of the 40 extremities of one of the circuit wires 106. The plug members 112 are mounted in an insulating block 114 secured to the lower portion of the horn proper, as shown in Fig. 2. This construction enables the wax 45 receptacle to be moved away from the base of the horn to give access to the parts within the lower portion of the horn and at the top of the horn spindle, or to be removed from the machine without disturbing 50 the arrangement of the electrical circuits. When the wax receptacle is moved outwardly from the lower portion of the horn along the horn base 10 the plug members 108 are withdrawn from the plug members 112 by the sliding movement of the receptacle, 55 thereby disconnecting or breaking the circuit for the heating unit 86. When the wax receptacle is moved from its outer position on the horn base to its normal position 60 adjacent the lower portion of the horn, as shown in Fig. 1, the plug members 108 are inserted in the sockets in the plug members 112 by the movement of the wax receptacle.
- 65 The circuit wires 106 extend from the plug members 112 through a suitable passage-way in the insulating block 114 and are respectively connected with the binding posts 116 mounted on the insulating plate 120 fixed to the base of the horn proper. 70 The terminal wires 100 of the electrical unit 98 are also respectively connected with the binding posts 116, as shown in Fig. 2. To the binding posts 116 are connected respectively the upper extremities of the circuit 75 wires 122 through which the current from the main circuit terminals passes in its course to the heating units. The heating units are thus arranged in parallel and the current passing from the main circuit terminals through the circuit wires 122 is divided at the binding posts 116 and passes therefrom through the respective heating units 86 and 98. In order that an efficient and reliable connection may be maintained 80 at all times between the electrical units in the horn and the main circuit leads or conductors which will not interfere with the rotation of the horn, a pair of distributor rings, respectively connected with the circuit wires 122 are mounted upon the lower end of the horn spindle, and a pair of brushes, respectively connected with the terminals of the main circuit leads, are arranged to bear respectively upon the distributor rings. 90
- The circuit wires 122 extend downwardly from the binding posts 116 through tubes 124 mounted in the horn spindle and are connected at their respective lower ends 100 with the distributor rings 126 mounted on the hollow shaft 18 forming part of the horn spindle. These distributor rings are made of some good conducting material such as brass or copper, and are mounted 105 upon the hollow shaft 18 so that they are insulated from each other and from the shaft. To support these rings a sleeve 128 is fixed by a set screw 130 to the hollow shaft 18 and upon this sleeve are 110 mounted the insulating rings 132. These distributor rings 126 are mounted respectively upon the peripheries of the insulating rings 132, are separated from each other by the intermediate insulating ring 115 134, and are each secured by the screws 136 to the ring 134. The lower insulating ring 132 bears against a shoulder at the lower end of the sleeve 128, and a nut 138 is threaded on the upper end 120 of the sleeve and serves to hold the parts securely on the sleeve. The circuit wires 122 are respectively connected with the distributor rings 126 by means of the binding screws 140. Arranged to bear respectively upon the distributor rings 126 are brushes 142 respectively mounted upon brackets 144 secured to an insulating block 146 fixed to the frame of the machine. 125 Each of these brushes is mounted in a sleeve 130

148 threaded into the corresponding bracket 144 and is yieldingly engaged with the distributor ring by means of a coiled spring 150 interposed between the inner end of the 5 brush and the end of the bore in the sleeve. The sleeves 148 are each surrounded by an insulating sleeve 152. Upon each of the brackets is mounted a binding post 153 and to these binding posts are attached the respective lower extremities of the circuit 10 wires 154. The upper end of one of the circuit wires 154 is connected with one of the terminals of a rheostat 156. The other terminal of the rheostat is connected by the 15 circuit wire 158 with one of the terminals of the main cut-out switch 160. The other circuit wire 154 is connected directly at its upper end with the other terminal of the main cut-out switch. This arrangement of 20 the rheostat enables the heat generated in both of the heating coils to be easily and conveniently controlled. The switch 160 is connected at the fuse box 161 with the main circuit terminals to which lead the main circuit 25 wires 162.

In order to protect the terminal wires 88 leading from the heating unit 86 from wax, with which the top and sides of the wax receptacle often become coated, a trough 164 shaped as shown particularly in Figs. 4 and 30 5 is mounted upon the wax receptacle for the reception of these wires and is closed by a cover 166 secured thereto by the screws 168. When the electrical unit 86 is to be removed from the arm 82 in which it is 35 mounted, the screws 168 are loosened and the cover 166 is removed from the trough.

Having explained the nature and object of the invention, and having specifically described 40 a machine embodying the same in its preferred form, what is claimed is:—

1. A wax thread sewing machine having, in combination, stitch forming devices, a support for the wax receptacle, a wax receptacle 45 slidable on said support, an electrical heating device for the wax receptacle, and circuit connections therefor comprising a plug member carried by said support, and a coöperating plug member carried by the 50 wax receptacle arranged to be engaged with and disengaged from the plug member carried by said support by the sliding of the wax receptacle along the support.

2. A wax thread sewing machine having, 55 in combination, stitch forming devices, a rotatable horn, a support for the wax receptacle mounted on the horn, a wax receptacle slidable on said support, an electrical heating device for the wax receptacle, and 60 circuit connections therefor comprising a plug member carried by said support, and a coöperating plug member carried by the wax receptacle arranged to be engaged with and disengaged from the plug member car-

ried by the support by the sliding of the 65 wax receptacle along the support.

3. A wax thread sewing machine having, in combination, stitch forming devices, a wax receptacle, an electrical heating device for the wax receptacle, electrical conductors 70 leading thereto, and a box-like structure mounted on the receptacle and having a removable cover for inclosing said conductors to protect the same from wax.

4. A sole sewing machine having, in combination, stitch forming devices, a rotatable horn, a wax receptacle, an electrical heating coil for heating the horn, an electrical heating coil for the wax receptacle, main circuit terminals, circuit connections for connecting 75 said coils with the main circuit terminals in parallel, and a rheostat for controlling the heat generated in both said coils.

5. A wax thread sewing machine, having, in combination, stitch forming devices, a wax receptacle, devices for guiding the thread through the receptacle, an electrical heating device for the wax receptacle having a chamber therein, an electrical heating unit mounted in the chamber, a trough 90 mounted on the receptacle and leading to the chamber, electrical conductors mounted in the trough and connected with the heating unit, and a removable cover for the trough. 95

6. A wax thread sewing machine, having, in combination, stitch forming devices, a wax receptacle, a cover for the wax receptacle, a thread guide carrying arm mounted on the cover and extending downwardly therefrom into the wax receptacle, thread guiding devices supported wholly on 100 said arm and arranged to guide the thread through the receptacle in proximity to said arm, a heating arm mounted on the cover and extending downwardly therefrom into the wax receptacle substantially parallel with the first arm for heating the wax in the receptacle and for heating the first arm and a series of radially extending heat radiating plates carried by and extending lengthwise of the heating arm. 105

7. A wax thread sewing machine, having, in combination, stitch forming devices, a wax receptacle, a cover for the wax receptacle, a thread guide carrying arm mounted on the cover and extending downwardly therefrom into the wax receptacle, thread guiding devices supported wholly on 115 said arm and arranged to guide the thread through the receptacle in proximity to said arm, and a connecting web between the thread guide carrying arm and the heating arm, extending lengthwise of said arms for conducting heat from the heating arm to the 120 thread guide carrying arm. 125

8. A sole sewing machine, having, in combination, stitch forming devices, a rotatable

horn, a horn spindle, a wax receptacle, an electrical heating coil for heating the horn, an electrical heating coil for the wax receptacle, secondary circuit conductors for said heating coils, primary circuit terminals mounted on the horn with which the conductors for said heating coils are connected in parallel, distributer rings mounted on the horn spindle, primary circuit conductors connecting said terminals with the distributer rings, brushes arranged to bear on the distributer rings, primary circuit conductors connected with the brushes, and a rheostat connected with the primary circuit conductors for controlling the heat generated in both the heating coils.

9. A wax thread sewing machine, having, in combination, stitch forming devices, a support for the wax receptacle, a wax receptacle mounted on the support, an electrical heating device for the wax receptacle, main circuit terminals, electrical conductors mounted on the support and connected with the main circuit terminals, electrical conductors connected with said heating device, and coöperating plug members for connecting the first conductors with the second conductors so as to permit the receptacle to be moved on the support or removed from the support.
